UNITED STATES PATENT OFFICE.

JOHN VAN NOSTRAND DORR, OF DENVER, COLORADO.

APPARATUS FOR THE DISPOSAL OF TAILINGS.

1,103,352.

Specification of Letters Patent. Patented July 14, 1914.

Application filed June 21, 1913. Serial No. 775,135.

To all whom it may concern:

Be it known that I, JOHN VAN NOSTRAND DORR, a citizen of the United States, residing in Denver, in the county of Denver and State of Colorado, have invented certain new and useful Improvements in Apparatus for the Disposal of Tailings, of which the following is a specification.

Ordinarily the tailings or residues from ore reduction works in mining operations, consisting of pulverized rock and the like from which the values have been extracted, are discharged from the mill in a solid condition by trams or belt conveyers, or are carried out suspended in a stream of water. When dry or solid they are usually trammed from the plant and dumped thus making a dump with a flat surface, or are carried up an incline by belt conveyers and deposited on a dump of increasing height. When water is employed to convey the tailings from the mill, they are usually led to a river or running stream, when such is available and not prohibited; but where a running stream cannot for any reason be used and it is necessary to confine the dump on certain ground, it has been the practice to construct dams in various ways at the foot of slopes on the available ground and to sluice the tailings down the slopes into the dams, where they settle and the surplus water is drawn off. This method of procedure requires the employment of considerable labor. There is great waste of water, by evaporation and otherwise, which might advantageously be used in the mill and there is danger of damage by the breaking of the dams.

My invention relates to the disposal of tailings, conveyed in suspension in water from the mill, and it consists in first extracting as much water as possible, to be returned to the mill for reuse if desired, and then distributing the thickened tailings in such manner as to form a dump, with its upper surface being extended out over the slope essentially horizontally, and the descending pulp building up the sloping surface similar to a dry dump. In this way the water will separate from the solid material, soaking into the dump or evaporating, and a pile or dump may be formed without an excessive flow of water, requiring the construction of dams.

The apparatus which I preferably employ comprises a decanter or thickener, which ex-

tracts some of the water from the tailings, and a distributor, which is connected with the thickener and delivers the thickened tailings to the dump. The thickener may be of any approved pattern, many apparatuses of this kind being well known to those skilled in the art of treating ore pulp for a similar purpose. The distributor is so constructed that it will deliver the thickened but still fluid tailings in small streams or jets, continuously or intermittently as desired, over an extended surface from the edge of the dump, so that as it flows down the water will separate from the solids by infiltration and evaporation. I have also found that the introduction of a storage vat for the thickened pulp, after the thickener, allows an accumulation of thick pulp for a given period, which may be rapidly discharged into the distributor at intervals, and thus enable the more rapid flow of thick material to run down the slope. The distributor is so mounted and supported that it may be moved from time to time as the dump is extended, and preferably it is made in sections, so that if necessary one section may remain idle to allow the surface of the dump to settle and dry while another is in operation. While perforated launders or perforated stationary pipes can be used for distributing the pulp, they require a heavy inclination with thick pulp, and I have found that when the distributor comprises an almost horizontally arranged perforated pipe, which is rotated during discharge, better results are obtained as the perforations are in this way kept free and the discharge is more uniform. The pipe connections are provided with suitable valves and the density of the discharge may be regulated to carry the thickened tailings to a greater or less distance down the incline of the dump, as may be desired.

In the accompanying drawings I have shown suitable apparatus for carrying out my invention.

Figure 1 is a perspective view of an ore milling plant, showing the combined thickener, storage tank and distributor, the latter being supported at the top of a slope where the dump is to be formed. Fig. 2 is a detail view illustrating how the layers of the dump are successively produced.

A mill is indicated at A and this delivers the tailings in water by a conveyer B to a

thickness C, where water is extracted and returned by a conductor D to the mill for reuse. The thickened pulp passes from the thickener or dewaterer by a pipe E to storage tank J, and thence by pipe E' to the distributing apparatus. This is suitably constructed to deliver the tailings in relatively small streams or jets to the dump. Preferably the distributor is constructed as follows:

10 It is divided into two or more sections in order that one section may be discharging while another is idle, and each section preferably consists of an approximately horizontally arranged perforated pipe F supported 15 on weighted skids G. It will be noted that the even distribution of the pulp can be further regulated by plugging up a portion of the perforations in the pipe from time to time, thus changing the flow over any given 20 portion of the dump. Each pipe section is arranged to rotate about a horizontal axis in bearings g on said skids. Each pipe F is connected to a branch e from the pipe E', and each branch is provided with a valve e'.

25 A motor H of any suitable kind, as an electric motor, is belted to each pipe section for the purpose of rotating it.

When the distributor is supported at the top of a slope in the manner shown in Fig. 1, 30 the tailings are first conveyed from the mill to the thickener, the extracted water being returned to the mill for reuse, while the thickened pulp is conveyed by the pipe E to storage tank J and then by pipe E' and 35 branches e to the pipes F through the perforations of which they pass and are delivered to the dump. During the operation the pipes are rotated by the motors in order to keep the perforations clear and to promote the 40 flow of pulp from the receiving ends to the opposite ends thereof and from time to time the skids and motors are moved forward to cause the deposit of successive layers on the dump in the manner illustrated in Fig. 2.

45 In this way much of the water from the mill is recovered and can be returned for reuse and the tailings freed from excess of water are deposited at any desired distance from the mill without the construction of dams 50 or the contamination of streams.

The method herein described is not claimed herein but claims thereto are made in my

application for Patent No. 719,464, filed Sept. 9, 1912.

I claim as my invention:

1. The combination of a thickener to which the wet tailings pass from a mill and which partially dewater the tailings, means for conducting back to the mill the extracted water for re-use, and a distributor which receives the thickened tailings from the thickener and delivers them to a dump. 55

2. The combination of a thickener to which the wet tailings pass from a mill and which partially dewater the tailings, means for conducting back to the mill the extracted water for re-use, and a distributor which receives the thickened tailings from the thickener, consisting of a perforated pipe arranged approximately horizontally and connected with the thickener, and means for rotating said perforated pipe. 60

3. The combination of a thickener receiving wet tailings from a mill and which partially dewater the tailings, means for saving the water extracted from the tailings, a perforated pipe arranged approximately horizontally and which receives tailings from the thickener, means for rotating the pipe, and counterbalanced supports for the pipe 70 adapted to hold the latter at the edge of a dump. 75

4. An apparatus for the disposal of tailings, comprising a thickener for partially dewatering them, a vessel adapted to store the thickened tailings and to discharge the same at suitable intervals, and means for distributing the thickened tailings along the edge of a dump. 80

5. An apparatus for the disposal of tailings, comprising a thickener for partially dewatering the tailings, a vessel for storing the thickened tailings and for discharging them at suitable intervals, perforated pipes and means for rotating said pipes to distribute the thickened tailings along the edge of a dump. 90

In testimony whereof, I have hereunto subscribed my name.

JOHN VAN NOSTRAND DORR.
